UNITED STATES PATENT OFFICE

143,082

DESIGN FOR A BATHING SUIT

Tina Leser, New York, N. Y.

Substituted for abandoned application Serial No.
116,322, November 14, 1944. This application
August 6, 1945, Serial No. 121,271

Term of patent 3½ years

(Cl. D3—17)

To all whom it may concern:

Be it known that I, Tina Leser, a citizen of the United States, residing in New York city, in the county of New York and State of New York, have invented a new, original, and ornamental Design for a Bathing Suit, of which the following is a specification, reference being had to the accompanying drawing, forming part thereof.

Fig. 1 is a front view of a bathing suit showing my design,

Fig. 2 is the rear view of the bathing suit shown in Fig. 1, and

Fig. 3 is a plan view of the brassière portion of the bathing suit shown in Fig. 1.

This application is a substitute for abandoned application Ser. No. 116,322, filed November 14, 1944.

The characteristic feature of my design resides in the combination on the bathing suit disclosed of the specific front opening brassière portion which is shaped and striped as shown.

I claim:

The ornamental design for a bathing suit, substantially as shown and described.

TINA LESER.
